UNITED STATES PATENT OFFICE.

SAMUEL CLARKE, OF CHILD'S HILL WORKS, COUNTY OF MIDDLESEX,
ENGLAND.

CANDLE-LAMP AND CHANDELIER.

SPECIFICATION forming part of Letters Patent No. 352,296, dated November 9, 1886.

Application filed December 14, 1885. Serial No. 185,606. (No model.) Patented in England September 23, 1885, No. 11,353; in France December 4, 1885, No. 172,717; in Germany December 5, 1885, No. 36,679; in Belgium December 7, 1885, No. 71,120, and in Austria May 3, 1886, No. 36/795.

To all whom it may concern:

Be it known that I, SAMUEL CLARKE, of Child's Hill Works, in the county of Middlesex, England, have invented certain new and useful Improvements in Candle-Lamps and Chandeliers, (for which I have obtained Letters Patent in England, dated September 23, 1885, No. 11,353; in France, dated December 4, 1885, No. 172,717; in Belgium, dated December 7, 1885, No. 71,120; in Germany, dated December 5, 1885, No. 36,679, and in Austria, dated May 3, 1886, No. 36/795,) of which the following is a specification.

The object of my invention, mainly, is to provide candle-lamps and chandeliers suitable for burning short candles of large diameter singly or in groups of any desired number; and to this end my improvements consist in novel constructions and combinations 20 of devices, hereinafter specifically designated by the claims.

In the accompanying drawings, Figure 1 shows a side elevation, Fig. 2 a vertical section, and Fig. 3 a horizontal section, of one 25 of the candle-lamps of the group. Fig. 4 is a side elevation, and Fig. 5 a view partly in plan and partly in section, of a small chandelier. Fig. 6 is a perspective view of a chandelier consisting of several groups or clusters 30 of candle-lamps. Fig. 7 is a similar view of a stand-lamp. Fig. 8 is a sectional view of a modified form of lamp-cup.

Each of the lamps of a group or cluster of any desired number consists of an outer lamp-cup, A, made of glass, the cavity of which is adapted to receive the short candle in an inner glass cup, D, which is of a capacity suitable for holding the fatty material composing the candle when it becomes melted, as it soon 40 does after lighting the candle. The lamp-cups are provided with horizontal annular flanges B', upon which rest the glass domes B, having open tops. The annular horizontal flanges B' are corrugated upon their upper surfaces, in order that air to supply combustion may be admitted beneath the lower edges of the glass domes.

There are projections standing up from the horizontal flange at its inner surface, to keep the

glass dome in place, and for a like purpose each 50 lamp-cup A is provided with an upright annular flange, A', surrounding the corrugated horizontal surface of the flange B'.

The modified form of lamp-cup is shown as provided with a downwardly-projecting lug, 55 h, by which to engage it with a socket in the outer end of an arm, h', forming a part of the chandelier or lamp-frame; but instead of forming the lamp-cup to be supported as just described I prefer to provide a series of supporting-rings, E, constituting a part of the lamp or chandelier frame, into which rings the lamp-cups are dropped, and supported by their annular shoulders b beneath their corrugated surfaces.

As shown in Figs. 4 and 5, the metallic rings E are carried by arms of the lamp or chandelier frame, projecting from a central boss, F, of the frame. A rod, G, with a ring, H, at its upper end, by which to suspend it, is connected at its lower end by a screw-thread and nut with the boss F. The suspending-rod G is reduced in diameter at its lower end and threaded, so that, as will be readily understood, the nut upon its lower end, together with the shoulder formed in reducing its size, will hold the boss securely in place. In this way the suspending-rod may be readily detached from the boss to facilitate packing the articles.

Figs. 6 and 7 represent, respectively, a chandelier provided with several clusters or groups of lamps and a stand-lamp similarly provided. In Fig. 6 the suspending-rod has the clusters of different diameters and numbers of lamps connected to it by means of their bosses 85 F, screwed in place upon the suspending-rod, and kept at the desired distance apart by tubular distance-pieces J, the screw-nut I serving to clamp the parts together.

The construction represented by Fig. 7 is 90 the same as that shown at Fig. 6, except that a lamp stand or base is provided, and there are two instead of three clusters of candle-holders.

By my improvements it will be seen that 95 when the candles are lighted they soon become melted, the glass domes (usually of tinted glass) confining and reflecting heat toward the

candles, and light passing through the liquid fatty material and freely through the glass sides and bottoms of the lamps gives a bright luminous appearance to the lamps when viewed 5 from below, which is especially advantageous for decorative purposes. It will also be seen that a readily-separable chandelier or lamp is provided and provision made for keeping the parts clean.

10 I am aware that it is not new, broadly considered, to provide a candle support or holder with a chimney or globe in which provision is made for supplying air to the base of the globe or chimney surrounding the candle, and

15 I do not claim, unqualifiedly, the combination of a candle-holder and a globe surrounding the candle therein with provision for the admission of air to the globe.

20 I am also aware that prior to my invention lamps and candle-holders had been supported by arms branching out from a central stem or stand, and I do not broadly claim such construction.

I claim as of my own invention—

25 1. The combination of the glass lamp-cup A, provided with the horizontal corrugated annular flange B' and a vertical annular flange, A', surrounding said corrugated flange, with the glass dome supported upon the corrugated 30 flange within said vertical flange, substantially as and for the purpose set forth.

2. The combination of the glass lamp-cup provided with the horizontal corrugated flange and the vertical flange, the inner glass cup, D, and the glass dome, substantially as and for 35 the purpose set forth.

3. The combination of a group of glass lamp-cups, containing the glass candle-holding cups D, and constructed, as described, each with a horizontal corrugated annular flange and the 40 surrounding vertical flange, with the glass domes, and a rod, G, and the arms radiating from said rod and supporting the lamp-cups at their outer ends, as and for the purpose set forth.

4. The combination of the series of glass lamp-cups A, each having the horizontal corrugated annular flange and the vertical annular flange, the inner glass cups, D, received in the cavities of the lamp-cups, the glass domes 50 resting upon the horizontal flanges of the lamp-cups, the lamp or chandelier rod, and the arms connected therewith, and provided with the rings for receiving the lamp-cups and holding them by their annular shoulders, substantially 55 as and for the purpose set forth.

SAMUEL CLARKE.
